UNITED STATES PATENT OFFICE.

WILLIAM ADAMS DELANO, OF NEW YORK, AND ELEANOR ROBSON BELMONT, OF HEMPSTEAD, NEW YORK.

RECEIVER-HOLDING ATTACHMENT FOR TELEPHONES.

1,170,421.

Specification of Letters Patent.

Patented Feb. 1, 1916.

Application filed February 11, 1915. Serial No. 7,563.

To all whom it may concern:

Be it known that we, WILLIAM ADAMS DELANO and ELEANOR ROBSON BELMONT, citizens of the United States, and residents, respectively, of the city of New York, borough of Manhattan, in the county and State of New York, and Hempstead, in the county of Nassau and State of New York, have invented a new and Improved Receiver-Holding Attachment for Telephones, of which the following is a full, clear, and exact description.

This invention relates to attachments to telephones for holding the telephone receiver in such relation to the transmitter that a person can use the telephone without the necessity of supporting the receiver to the ear by the hand, as is now commonly necessary, and as a result both hands will be free for any desired employment during a telephone intercourse.

The invention has for its general objects to improve and simplify the construction of devices of the character referred to so as to be reliable and efficient in use, comparatively inexpensive to construct, and so designed that they can be applied to the various types of telephones and by persons of ordinary intelligence.

A more specific object of the invention is the provision of a receiver holding attachment for telephones in which the attachment embodies a clamping ring, or clip which is applied to and clamped on the body of the telephone transmitter, and projecting laterally from the clip or ring are spring jaws so shaped as to effectively hold the grip portion of the receiver, while the diaphragm portion of the receiver will be so related to the transmitter that while the receiver is adjacent the ear of the user the mouth will be in suitable proximity to the transmitter, so that the voice can be directed into the latter, and as the receiver is, by means of the attachment, supported on the body of the transmitter, the hands of the person using the telephone are left free for various purposes, and the tiresome act of holding the receiver to the ear is obviated.

With such objects in view, and others which will appear as the description proceeds, the invention comprises various novel features of construction and arrangement

of parts such as will be set forth with particularity in the following description and claims appended hereto.

In the accompanying drawing, which illustrates one embodiment of the invention, and wherein similar characters of reference indicate corresponding parts in all the views, Figure 1 is a perspective view of a desk telephone with the attachment applied to the transmitter body, and the receiver being shown by full lines supported on the switch hook, and by dotted lines on the attachment; Fig. 2 is a plan view of the attachment, showing the same supporting the receiver of the telephone; Fig. 3 is a perspective view of the attachment removed; and Fig. 4 is a vertical section through the clip or clamping ring of the attachment.

In the present instance the attachment is shown in connection with a desk type of telephone, but it is to be understood that it is applicable to other forms.

Referring to the drawing, A designates a receiver and B the transmitter of a telephone set, and applied to the body of the transmitter is the attachment C, which constitutes the subject matter of the present invention. The purpose of this attachment is to support the receiver, when the telephone is in use, in such a manner that a conversation can be conducted through the telephone without the user having to hold the receiver in the hand, as is now commonly necessary. When the attachment is not in use the receiver A is supported in the usual manner on the switch fork 1 of the telephone.

The attachment C comprises an attaching ring or clip 2 which is made in two semi-circular parts 3 and 4 riveted together at 5, and at 6 being provided with outwardly extending lugs 7 and 8 which are provided with a screw 9 or equivalent tightening device. The semi-circular members 3 and 4 tend to spring apart so that the ring will be of large enough diameter to slip on the body of the transmitter B, and when the ring is properly applied, the screw 9 is turned so as to contract the ring and thereby clamp the same circumferentially around the body of the transmitter. The ring is made of sheet metal and the front edges of the members 3 and 4 are bent into internal

flanges 10 which engage the front face *b* of the transmitter body and determine the proper positioning of the ring on the latter.

The attaching ring 2 is formed with laterally projecting gripping jaws 3^a and 4^a, oppositely bowed so that they can obtain a firm grip on the handle portion *a* of the receiver.

A. The free extremities of the jaws are backwardly curved into lips 3^b and 4^b, which lips are spaced apart so as to constitute an open mouth somewhat smaller than the diameter of the grip portion *a* of the receiver. A, and preferably, although not necessarily, the lower lip 4^b projects somewhat beyond the lip 3^b, whereby the insertion of the receiver is facilitated. In inserting the receiver the same comes into contact with the two lips, and these spring apart as the receiver is forced into the jaws, and as soon as the receiver is fully inserted the jaws close, by means of their resiliency, on the receiver and firmly hold the same. These jaws have considerable width so as to provide large bearing surfaces for the receiver. The jaws 3^a and 4^a are preferably integrally connected with the sections 3 and 4 of the attaching ring 2, and the jaws are united with their respective ring sections by flat portions 12 which are brought together and fastened by a rivet 13.

When the telephone is in use the receiver is held by the jaws, as shown by dotted lines in Fig. 1, and the relation of the effective part of the receiver to the transmitter is such that voice sounds can be reliably received and transmitted. The placing of the receiver in the jaws and the removing of the receiver therefrom requires but little effort and can be done with one hand.

From the foregoing description taken in connection with the accompanying drawing, the advantages of the construction and method of operation will be readily understood by those skilled in the art to which the invention appertains, and while we have described the principle of operation, together with the device which we now consider to be the best embodiment thereof, we desire to have it understood that the device shown is merely illustrative, and that such changes may be made when desired as fall within the scope of the appended claims.

Having thus described our invention, we

claim as new and desire to secure by Letters Patent:

1. A telephone attachment comprising a clamping ring for application to a transmitter body, said ring being provided with an internal flange for engaging the front of the body to determine the proper positioning of the ring and also for stiffening the said ring, and a pair of jaws integrally connected with the ring and extending laterally therefrom to hold a receiver during the use of the telephone to which the attachment is applied.

2. A receiver attachment for telephones, comprising a clamping ring expandible and contractible, said ring having at its front edge an internal flange adapted to engage the front face of a telephone transmitter, and laterally projecting spring jaws for holding a receiver, the free ends of the jaws being spread apart, and the lower jaw projecting beyond the upper jaw, said flange insuring the placing of the attachment on the transmitter in a position with the longer jaw lowermost when the jaws project from the left of the transmitter.

3. A receiver holding attachment for telephones, consisting of two sections, each section being made of a single strip of metal and bent into a semi-circular part, and a bowed jaw, the jaw being united with one extremity of the semi-circular part by a flat portion, and the opposite extremity of the semi-circular part being formed into an apertured lug, a fastener for permanently securing the flat parts of the sections together, and a tightening device passing through the apertured lugs, said semi-circular parts being formed with internal flanges for insuring the proper positioning of the attachment on the body of a transmitter and the jaws having oppositely curved lips, and the lower lip extending outwardly beyond the other.

In testimony whereof we have signed our names to this specification in the presence of two subscribing witnesses.

WM. ADAMS DELANO.
ELEANOR ROBSON BELMONT.
